H. A. WALLACE

RAILWAY TRAFFIC CONTROLLING APPARATUS

Filed Aug. 21, 1923

UNITED STATES PATENT OFFICE.

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 21, 1923. Serial No. 658,553.

My invention relates to railway traffic controlling apparatus, and particularly to apparatus of the type comprising train carried governing means controlled by energy received from the trackway. More particularly my invention relates to the trackway portion of such apparatus.

I will describe one form and arrangement of apparatus embodying my invention, and will then point out the novel features thereof in claims.

The accompanying drawing is a diagrammatic view showing one form of apparatus embodying my invention.

Referring to the drawing, the reference characters U and V designate two railway tracks which merge at a switch N into a stretch of track Q. Traffic normally moves in the direction indicated by the arrow. The track Q to the right of switch N is adapted to be used by traffic whose speed and tonnage divides it into two separate classes. For example, these two classes may be light multiple-unit electric trains having relatively short maximum braking distances, and heavy high speed steam trains having relatively long maximum braking distances.

In the following description I will assume that all the lighter traffic approaches the track Q over the track U, and that all the heavy traffic approaches the track Q over track V.

The track Q and the approach track U are divided by insulated joints 2 into a plurality of successive track sections A—B, B—C, etc.

A signal S' located adjacent track V governs traffic of the heavy class into the stretch of track Q, a similar signal S^A located adjacent point A on track U governs traffic of the lighter class into the stretch of track Q, signals S^B, S^C and S^D govern movements of traffic of both classes through the stretch of track Q.

As here shown, each of the signals S comprises a semaphore arm capable of assuming three distinctive positions at 0°, 45° and 90° with respect to its mast whereby the signal displays a proceed, caution or stop indication respectively.

Each track section is provided with a source of track circuit current which comprises, as here shown, the secondary 8 of a track transformer designated by the refer-

ence character T with an exponent corresponding to the location and connected across the track rails adjacent the exit end of the section. The primary 9 of each track transformer is constantly supplied with alternating current from the secondary of a line transformer designated by the reference character H with an exponent corresponding to the location. The primary of each such line transformer H is constantly supplied with alternating current from a generator M over line wires 4 and 4^a. Interposed between the secondary 8 of each track transformer T and one rail, 1, of the associated section is an impedance 7 one function of which is to limit the output of the transformer when its terminals are short-circuited by the wheels and axles of a passing train. Each section is also provided with a track relay designated by a reference character R with an exponent corresponding to the location and comprising two windings 5 and 6. The winding 6 of each track relay is constantly supplied with alternating current from the associated line transformer H, and winding 5 of each track relay R is constantly connected across the rails adjacent the entrance end of the associated section. It is therefore clear that each track section is provided with a track circuit comprising the secondary 8 of a track transformer T, an impedance 7, a winding 5 of a track relay R and the rails 1 and 1^a of the section in series.

Associated with each track relay R is a stick relay designated by the reference character G with an exponent corresponding to the location. Each track section is further provided with an auxiliary relay located adjacent the exit end thereof and designated by the reference character K with an exponent corresponding to the location.

Referring particularly to stick relay G^A, this relay is provided with a pick-up circuit which passes from the secondary of line transformer H^A, through wires 12 and 27, contact 19—20 operated by signal S^A, wire 21, winding of relay G^A, and wires 22 and 3 back to the transformer H^A. This circuit is closed only when signal S^A is at caution or proceed under which circumstances relay G^A is energized. Relay G^A having been picked up, if relay R^A is de-energized, as by a train entering section A—B from the sec-

tion to the left of A, a retaining or stick circuit is closed which passes from the secondary of transformer H^A , through wires 12, 27 and 23, back contact 24 of relay R^A , wire 25, 5 front contact 26 of relay G^A , wire 21, winding of relay G^A , and wires 22 and 3 back to transformer H^A . This circuit is closed only when relay G^A is energized and relay R^A is de-energized, and relay G^A therefore remains 10 energized as long as any train entering track Q from point A. occupies this section. The closing of front contact 28 of stick relay G^A closes a pick-up circuit for the stick relay G^B for the section next in advance, which pick-up circuit is from secondary of transformer H^A through wire 12, front contact 28 of relay G^A , wire 29, winding of relay G^B and wires 30 and 3 back to transformer H^A . Relay G^B is provided with a retaining or stick 15 circuit which passes from the secondary of line transformer H^B , through wires 40 and 80, back contact 81 of track relay R^B , wire 82, front contact 83 of stick relay G^B , wires 84 and 29, winding of relay G^B , and wires 20 30 and 3 back to transformer H^B . A second stick circuit for relay G^B passes from the secondary of transformer H^A , through wires 12 and 23, back contact 91 of track relay R^A , wires 82^a and 82, front contact 83 of relay 25 G^B , wires 84 and 29, winding of relay G^B , and wires 30 and 3 back to transformer H^A . It will thus be clear that having once been 30 energized, relay G^B is maintained in its energized condition by the de-energization of 35 the associated track relay or of the track relay next in the rear. The stick circuit for relay G^C is similar to the stick circuit for relay G^B but the pick-up circuit for this relay passes from the secondary of transformer H^B , through wires 40 and 80, front contact 40 81 of track relay R^B , wire 87, front contact 86 of relay G^B , wire 89, winding of stick relay G^C , and wires 90 and 3 back to transformer H^B . Relay G^D is controlled over 45 circuits similar to those provided for relay G^C . It will be plain from the foregoing that the clearing of signal S^A to permit a train to enter track Q from track U causes the energization of all the stick relays G in succession, 50 provided none of the track sections in advance is occupied. If one of the track sections in advance is occupied, the corresponding track relay will be de-energized and none of the stick relays G to the right of the 55 relay G associated with such de-energized track relay will become energized. The purpose of the feature is to make it impossible for the moving of signal S^A to proceed or caution to permit the entrance into stretch Q, 60 of a train from track U to affect the control limits of a train already occupying the stretch if this train has entered from track V. The clearing of signal S' to permit a 65 train to enter track Q will not energize relays G.

Each of the signals S is provided with a caution circuit and a proceed circuit adapted when closed to cause the signal to display, respectively, a caution, or a proceed indication, and when neither such circuit is closed 70 the signal displays a stop indication. The operating mechanism is further arranged so that the proceed circuit is effective to cause the signal to display a proceed indication only when the caution circuit is already closed. 75

Referring particularly to signal S^B , this signal is provided with a caution circuit which passes from the secondary of transformer H^B , through wires 40 and 47, front contact 48 of track relay R^B , wire 49, operating mechanism of signal S^B , and wire 3 back to transformer H^B . The closing of the circuit just traced causes the signal S^B to display a caution indication thus closing contact 50-51. A proceed circuit for this signal is then closed (assuming signals S^C and S^D to be at caution or proceed), which circuit is from the secondary of transformer H^D , through wire 52, contact 53-54 operated by signal S^D , wire 55, contact 56-57 operated by signal S^C , wire 58, contact 50-51 operated by signal S^B , operating mechanism of signal S^B , and wire 3 back to transformer H^B . Another proceed circuit for signal S^B passes from the secondary of transformer H^C , through wires 31 and 59, front contact 60 of relay G^C , wires 61 and 55 and thence as before through the operating mechanism of signal S^B and by wire 3 back to transformer H^C . It is therefore evident that 90 when relay G^C is energized it removes signal S^D from the control of signal S^B . Signals S^C and S^D are provided with circuits similar in all respects to those just described for signal S^B . 95

As here shown signals S^A and S' are controlled in part by manually operable switch levers P^2 and P' , respectively, although these signals may be controlled by any suitable means automatic or otherwise. The two levers P' and P^2 are interlocked by means of any suitable kind so that only one of these levers may be moved into its operative or circuit closing position at a time thereby insuring that only one of the signals controlled thereby may be cleared at one time. If the operator wishes to clear signal S^A he moves lever P^2 into its circuit closing position thus closing the caution circuit for signal S^A (assuming section A-B to be unoccupied) and allowing current to flow from secondary of transformer H^A , through wires 12, 27, 13 and 14, front contact 15 of track relay R^A , wire 16, switch lever P^2 , wire 17, operating mechanism of signal S^A , and wires 18 and 3 back to transformer H^A . The movement of signal S^A to the caution indication energizes stick relays G and closes a proceed circuit for signal S^A which circuit passes from secondary of 125 130

transformer H^B , through wires 40 and 41, contact 42 of relay G^B , wires 43, 72 and 34, contact 35-36 operated by signal S^B , wire 37, contact 38-39 operated by signal S^A , operating mechanism of signal S^A , and wires 18 and 3 back to transformer H^B . The caution circuit for signal S' is controlled by switch lever P' in a manner analogous to that described for the control of signal S^A 10 by switch lever P^2 , but since the stick relays G are de-energized when this signal is at caution, the proceed circuit for signal S' passes from the secondary of transformer H^C , through wire 31, contact 32-33 operated by signal S^C , wire 34, contact 35-36 operated by signal S^B , wires 37 and 44, contact 45-46 operated by signal S' , operating mechanism of signal S' , and wire 3 back to transformer H^C . Since the energization of 20 relays G is dependent upon the indication displayed by signal S^A , and since only traffic of the lighter class is governed by this signal whereas all heavier traffic enters the single track stretch from track V and is governed by signal S' it follows that the 25 limits of the control of the signals S^B , S^C , S^D , etc. are automatically regulated in accordance with the class of traffic moving over the road.

30 In explaining the operation of the apparatus thus far described I will assume that a train occupies the section to the right of point D , thus de-energizing track relay R^D and opening at its front contact, the caution circuit for signal S^D . As hereinbefore stated, this causes the proceed circuits for this signal to become ineffective and the signal therefore displays a stop indication. As a result the proceed circuit for signal S^C 35 is broken by contact 62-63 operated by signal S^D but the caution circuit for signal S^C is complete and the signal therefore displays a caution signal. Signal S^B displays only a caution indication because its main proceed circuit is open at contact 53-54 on signal S^D and its auxiliary proceed circuit is open at relay G^C . If switch P^2 is now closed to cause signal S^A to display a proceed indication, the consequent energization 40 of the stick relay G^C allows signal S^B to move to the proceed position to permit light traffic moving into section $A-B$ at point A to travel at authorized speed as far as point C . If, however, switch P' is now operated 45 to clear signal S' , relays G will remain open, so that signal S^B will remain at caution, and a train accepting signal S' and entering the stretch of single track from track V will receive a caution indication at point B thus insuring sufficient distance in which to stop 50 the train before arriving at point D .

Means are also provided for supplying to the rails of each section a current which I shall hereinafter term a "local current". The immediate source of this local current

as here shown is a local transformer located adjacent the exit end of each section and designated by the reference character L with an exponent corresponding to the location. The primary 11 of each such transformer is constantly supplied with alternating current from the associated line transformer H . Each section is further provided with an impedance X connected across the rails adjacent the entrance end of the section, a similar impedance Z connected across the rails adjacent the exit end of the section, and a third similar impedance Y connected across the rails at an intermediate point in the section. Local current is supplied to the rails of the section from the mid points of these impedances.

Before proceeding further it should be pointed out that the trackway apparatus herein shown and described is intended for co-operation with train carried governing means in the following manner: When the train occupies a portion of track supplied with track circuit current and also with local current of normal relative polarity a proceed indication is received aboard the train; when the train is on a portion of track supplied with track circuit current and with local current of reverse relative polarity a caution indication is received aboard the train; and when the train occupies a stretch of track to which the supply of either track circuit current or local current is interrupted, a stop indication is received aboard the train. These proceed, caution and stop indications referred to above may be in the form of visual or audible signals, or may be effective to apply the brakes and automatically reduce the train to predetermined safe speeds. In the following discussion I will assume that the governing mechanism is of the latter type and allows the train to proceed at a high speed as 65 miles per hour when receiving a proceed indication, at an intermediate speed such as 35 miles per hour when the train is receiving a caution indication, but prevents the train from proceeding at more than a low speed as 15 miles per hour when the train is receiving a stop indication.

Each section is supplied with local current of one polarity or the other between its entrance end and its exit end or between its entrance end and an intermediate point therein depending on the condition of energization of the auxiliary relay K and the indication displayed by the associated signal. For this purpose each signal S is provided with a pole changer designated by the reference character J with an exponent corresponding to the location and adapted to assume one position when the associated signal indicates stop, and another position when the associated signal indicates proceed or caution. Auxiliary relay

K^p is provided with a circuit which passes from the secondary of transformer H^c through wire 31, contact 32-33 operated by signal S^c , wires 34, 72 and 73, winding of relay K^p , and wires 74 and 3 back to transformer H^c . This circuit is closed when signal S^c indicates proceed or caution, but not when it indicates stop. If, however, relay G^p is energized the closing of 10 its front contact completes a second circuit for relay K^p which circuit is from the secondary of transformer H^p , through wires 40 and 41, front contact 42 of relay G^p , wires 43 and 73, winding of relay K^p , and wires 74 and 3 back to transformer H^p . It is therefore clear when relay G^p is closed, relay K^p is closed regardless of the position of signal S^c . The control of the remaining auxiliary relays K is accomplished by circuits similar to those associated with relay K^p .

Referring now particularly to section C-D this section is provided with one local circuit which passes from secondary 10 of local transformer L^p , through wire 64, pole changer J^p , wire 65, front contact 66 of relay K^p , wires 67 and 67^a, impedance X in section C-D, thence through the rails of the section in parallel to impedance Z , wire 68, front contact 69 of relay K^p , wires 70, pole changer J^p , and wire 71 back to transformer L^p . This circuit is closed only when relay K^p is energized and signal S^p indicates caution or proceed, under which conditions the rails of section C-D are supplied with local current of normal relative polarity throughout their length. If however, relay G^p is de-energized and the next signal in advance of S^p is at stop, relay K^p will be de-energized and its two armatures 66 and 69 will operate as a pole changer to reverse the relative polarity of the local current supplied to the rails of section C-D. Another local circuit is provided for section C-D 45 when signal S^p , indicating stop, reverses the pole changer J^p , under which conditions current flows from secondary 10 of transformer L^p through wire 64, pole changer J^p , wire 75, impedance Y in section C-D, through the rails of the section in parallel to impedance X , wire 67^a, pole changer J^p , and wire 71 back to transformer L^p , thus supplying local current of reverse relative polarity to the rails of section C-D between impedances X and Y , but no local current between impedances Y and Z .

I will now assume that a train occupies the section to the right of D and that signal S^a is at proceed. Signal S^c will then be at 60 caution and signal S^p will indicate proceed, the route being set up for traffic of the lighter class. Pole changers J^p and J^c will each be in the normal position, pole changer J^p will be reversed, and all the stick relays G will be energized. If now a train enters the

stretch of track shown in the drawing at point A, the governing mechanism will allow it to proceed at high speed as far as point C at which point the reversal of local current will cause the train to receive a 70 caution indication in accordance with the position of signal S^c and the train speed will be reduced to 35 miles per hour. As the train passes impedance Y , the interruption of local current will cause a stop indication 75 to be transmitted to the train which will then be allowed to proceed only at speeds not in excess of 15 miles per hour.

I will now assume that a train occupies the section to the right of D, as before, but that signal S^a indicates stop and signal S' indicates proceed. Stick relays G are therefore de-energized with the result that signals S^p and S^c both indicate caution and relay K^c will be de-energized. If, now, a train of 80 the heavier class enters the stretch of track shown in the drawing from track V, it will be permitted to travel at high speed through section A-B. At point B, however, the reversal of local current due to the de-energization of relay K^c will cause the governing apparatus aboard the train to receive a caution indication and the speed of the train will then be reduced to 35 miles per hour. This intermediate speed limitation 85 continues in section C-D due to the reversal of pole-changer J^p as far as impedance Y in section C-D, where the interruption of the local current transmits a stop indication to the train and the speed of the 90 train is reduced to 15 miles per hour.

It will thus be seen that in my invention the signal control limits are automatically selected for traffic of different classes having different maximum braking distances and though I accomplish the selection in the 105 present case by admitting the traffic of the two classes to the track stretch from different roads, I do not wish to limit myself to this particular means of selection.

Although I have herein shown and described only one form and arrangement of railway traffic controlling apparatus embodying my invention, it is understood that various changes and modifications may be made therein within the scope of the appended claims without departing from the 115 spirit and scope of my invention.

Having thus described my invention, what I claim is:

1. In combination, a stretch of railway track to which traffic is admitted at the same point from separate routes, railway traffic controlling apparatus associated with said stretch, and means responsive to traffic conditions in said routes for controlling said apparatus.

2. In combination, a stretch of railway track to which traffic is admitted at the same point from separate routes, railway traffic 120

controlling apparatus associated with said stretch, means operative when a vehicle enters said stretch from one said route for controlling such apparatus, and means operative when a vehicle enters said stretch from another said route for modifying such control.

3. In combination, a stretch of railway track to which traffic is admitted at the same point from separate routes, means for imposing certain restrictions on traffic entering said stretch from one route, and means for imposing other restrictions upon traffic entering said stretch from a different route.

4. In combination, a stretch of railway track to which traffic is admitted over separate routes, a signal for governing traffic entering said stretch from one route, a second signal for governing traffic entering said stretch from a different route, traffic controlling apparatus associated with said stretch, and means controlled by one of said signals but not by the other for varying the operation of said apparatus.

5. In combination, a stretch of railway track, a source of local current, means operative when such stretch is occupied by traffic of one class for connecting said source with the rails of said stretch, and means operative when such stretch is occupied by traffic of another class for modifying said first means.

6. In combination, a stretch of railway track comprising three consecutive track sections each provided with a signal capable of displaying a stop, a caution, or a proceed indication, means operative when said stretch is occupied by a train of one class and the forward signal is at stop for causing the next signal in the rear to display a caution indication and the second signal in the rear to display a proceed indication, and means operative when said stretch is occupied by a train of another class and the forward signal is at stop for causing both of the remaining signals to indicate caution.

7. In combination, a stretch of railway track comprising an insulated track section, a relay controlled in accordance with the operating characteristics of traffic occupying such stretch, a signal for said section, and means controlled by said relay for operating said signal.

8. In combination, a stretch of railway track comprising an insulated track section, a relay controlled in accordance with the operating characteristics of traffic occupying such stretch, and means controlled by said relay for supplying local current to said section.

9. In combination, a stretch of railway track comprising an insulated track section, a relay controlled in accordance with the operating characteristics of traffic occupying such stretch, and means controlled at

times by said relay for supplying local current to said section.

10. In combination, a stretch of railway track comprising an insulated track section, a relay controlled in accordance with the operating characteristics of traffic occupying such stretch, an auxiliary relay controlled by said first relay, and means controlled by said auxiliary relay for supplying local current to the said section.

11. In combination, a stretch of railway track comprising an insulated track section, a relay controlled in accordance with the operating characteristics of traffic occupying such stretch, an auxiliary relay controlled by said first relay, and means controlled by said auxiliary relay and said first relay for supplying local current to the rails of said section.

12. In combination, a stretch of railway track, comprising an insulated track section, a relay controlled in accordance with the operating characteristics of traffic occupying such stretch, a signal for said section, a pole changer operated by said signal, an auxiliary relay controlled by the first said relay, a source of local current, and means controlled by said pole changer and said auxiliary relay for connecting said source with the rails of said section.

13. In combination, a stretch of railway track provided with signals, contact mechanism operated by each such signal, a stick relay for each signal, means for controlling said stick relays in accordance with the operating characteristics of the traffic occupying said stretch, and means including the stick relay associated with the signal next in advance and the contact mechanisms operated by the two signals next in advance for controlling each said signal.

14. In combination, a stretch of railway track, means for permitting traffic to enter said stretch from different routes, and means responsive to traffic conditions in said stretch for supplying the stretch with local current in accordance with the route from which a train occupying the stretch has entered it.

15. In combination, a stretch of railway track, means for permitting traffic to enter said stretch from different routes, and means for supplying the stretch with local current in accordance with the route from which a train occupying the stretch has entered it.

16. In combination, a stretch of railway track to which traffic is admitted at the same point from different routes, a stick relay, means for energizing said relay when said stretch is prepared to receive traffic from one of said routes but not from the other, means for subsequently keeping said relay energized while a train is approaching and entering said stretch over the said one route, traffic governing apparatus associated with said

stretch, and means responding to energization of said stick relay for modifying the normal operation of said apparatus.

17. In combination, a stretch of railway track comprising an insulated track section, a signal located at the forward end of said section and controlled by traffic conditions in advance, a pole changer operated by said signal, a relay whose energization depends upon the operating characteristics of traffic for which the stretch is prepared, means controlled by said pole changer for supplying local current of one relative polarity to a portion of said section, and means controlled by said pole changer and said stick relay for supplying current of one relative polarity or the other to the rails of the entire section.

18. In combination, a stretch of track divided into a plurality of successive sections, a signal for each section, a pole-changer operated by each signal, a stick relay and an auxiliary relay associated with each signal, means for energizing said stick relays when a train having relatively short maximum braking distance enters said stretch but not when a train having relatively long maximum braking distance enters the stretch, means for energizing each auxiliary relay when the associated stick relay is closed or when the next signal in advance indicates caution or proceed, and means for each section for supplying local current to the rails of the section from the entrance end to the

exit end when the signal for the next section is at clear or caution, said current being of normal or reverse relative polarity according as the auxiliary relay for such signal is closed or open, and said local current supplying means operating to supply current of reverse relative polarity from the entrance end to an intermediate point in the section when the signal next in advance indicates stop.

19. In combination, a stretch of railway track divided into a plurality of successive sections and to which ingress is afforded over different routes, a railway traffic controlling device for each said section, a stick relay for each section for controlling the associated traffic controlling device, and means effective when said stretch is occupied by a train which has entered the stretch over one route and a second train enters the stretch over a different route, to energize the stick relays in rear of said first train but not in front thereof.

20. In combination, a stretch of railway track, means for admitting to said stretch traffic having different braking characteristics, traffic controlling apparatus for said stretch, and mechanism controlled by said admitting means for modifying the control limits of said apparatus.

In testimony whereof I affix my signature.

HERBERT A. WALLACE.
